CLAIM

The ornamental design of a golf ball detector, as shown and described.

DESCRIPTION

FIG. 1 is a perspective view of a golf ball detector showing the new design with the wand portion fully retracted; FIG. 2 is a front elevational view of the FIG. 1 golf ball detector, the back, left and right side elevational views being substantially identical thereto;

FIG. 3 is a bottom plan view of the FIG. 1 golf ball detector, the top plan view being substantially identical thereto; FIG. 4 is a front elevational view of the golf ball detector, showing the wand in a partially extended position; FIG. 5 is a front elevational view of the golf ball detector, showing alternate positions of the ball element and the wand element;

FIG. 6 is a front elevational view of the golf ball detector of FIG. 1, with the wand element in a fully extended position; and,

FIG. 7 is a front elevational view of the golf ball detector of FIG. 6, with the wand element in an alternate fully extended position.
